LEVER OPERATED ROTARY BAR FASTENER

George E. Dath, Mokena, Ill., assignor to W. H. Miner, Inc., Chicago, Ill., a corporation of Delaware

Application January 11, 1947, Serial No. 721,600

4 Claims. (Cl. 74—523)

1

This invention relates to improvements in lever operated rotary bar fasteners for doors, and more particularly to fasteners of this type employed in connection with hinged doors.

One object of the invention is to provide a lever operated rotary bar fastener for a door of the hinged type, which is housed within the structure of the door to conceal the same and is particularly designed to provide for quick and easy application to the door.

A further object of the invention is to provide in a door fastener of the lever operated rotary bar type, simple and reliable means for securing the operating handle lever to the rotary bar of the fastener.

A more specific object of the invention is to provide a fastener of the character indicated in the preceding paragraph, wherein the operating lever is welded to the rotary bar in such a manner as to reduce torsional strains on the welded joint, thereby reducing the danger of breakage at said joint.

Other objects of the invention will more clearly appear from the description and claims herein-after following.

In the accompanying drawings forming a part of this specification, Figure 1 is a broken rear elevational view of the body portion of an automobile truck provided with hinged doors, illustrating my improvements in connection therewith. Figure 2 is a detailed view, on an enlarged scale, similar to Figure 1, of the left hand end of the right hand door at the mid portion thereof. Figure 3 is a horizontal sectional view, corresponding substantially to the line 3—3 of Figure 2. Figure 4 is a vertical sectional view, through the left hand end portion of the right hand door shown in Figure 1, said view being taken on the line 4—4 of Figure 3. Figures 5 and 6 are plan views of the upper keeper and the cooperating keeper engaging member of my improved door fastener, as illustrated in Figure 1, Figure 5 showing the keeper engaging member partly engaged with the keeper and Figure 6 showing the same completely engaged and in door locking position. Figure 7 is an elevational view, on an enlarged scale, of the portion of the operating bar to which the handle lever is attached, showing said bar before the lever is applied thereto. Figure 8 is a horizontal sectional view, corresponding substantially to the line 8—8 of Figure 7. Figure 9 is a horizontal sectional view of the rotary bar and operating lever, on an enlarged scale and partly broken away, corresponding substantially to the line 9—9 of Figure 2. Figure 10

2

is a view, similar to Figure 9, showing another embodiment of the connecting means for the bar and operating lever.

In said drawings, 10 indicates the rear end wall of the body of an automobile truck. The wall 10 is provided with the usual opening 11, closed by a pair of swinging doors 12 and 13, supported along their outer edges by the usual hinges 14—14. The doors 12 and 13 are of a well-known type employed on automobile trucks. The door 12, as shown, comprises spaced front and rear walls 15 and 16 made of sheet metal, connected by top and bottom Z-bars 17—17 which form the top and bottom walls of the door. At the inner and outer edges, the front and rear walls 15 and 16 of the door 12 are connected by the usual vertical end walls, the wall at the inner edge only being shown. This wall is indicated by 18.

The construction of the door 13 is similar to that of the door 12 and the meeting edges of the two doors are beveled so that the door 12 overlaps the door 13 when the doors are fully closed. My improved door fastener is carried on the door 12, and the front wall 15 of said door is provided with an inwardly offset section 19 between the top and bottom of the door adjacent the inner edge portion thereof, forming a laterally elongated pocket 20, adapted to receive the operating handle lever of my improved door fastener, as hereinafter pointed out.

Referring first to the embodiment of the invention illustrated in Figures 1 to 9 inclusive, my improved door fastener, as shown, comprises broadly an operating bar A, keeper engaging end members B—B at opposite ends of the bar, an operating handle lever C fixed to the bar, and keepers D—D with which the end members B—B are engageable.

The operating bar A is in the form of an elongated tube of circular cross section, housed within the door 12, being arranged vertically between the front and rear walls and extending through aligned bearing openings 22 and 23 in the top and bottom walls 24 and 25 of the pocket 20.

The keeper engaging end members B—B are mounted, respectively, on the top and bottom ends of the bar A. Each member B comprises a keeper engaging finger 26 and a cylindrical shank or stem 27 from the outer end portion of which the finger extends radially. The cylindrical shank or stem of each end member is telescoped within the corresponding end of the tubular bar A and fixed thereto by being welded, the wall of the tubular bar A being provided with suitable openings 28 to receive the welding metal 29. The

keeper engaging fingers 26 are of well-known design and cooperate with the top and bottom keepers D—D in the usual manner to force the door open and closed, the keepers D—D, which are located in the walls of the door opening immediately above and below the door 12, being provided with the usual L-shaped openings or slots within which the fingers 26—26 are engageable.

The end members B—B of the tubular operating bar A protrude beyond the top and bottom edges of the door to properly cooperate with the keepers D—D. As shown in Figure 4, the top and bottom ends of the bar A are journaled in suitable bearing openings 30—30 in the horizontal webs of the top and bottom Z-bars 17—17, and the bar is supported against downward displacement by a collar 31 fixed to the bar and resting on the bottom wall 25 of the pocket 20. The collar 31 is preferably welded to the bar, as indicated by 32. The collar 31 is cut way or slotted on one side, as shown at 131, for a purpose herein-after pointed out.

The operating lever C is secured to the bar A between the top and bottom ends thereof, being carried by that portion of the bar which extends through the pocket 20. This handle lever is in the form of an elongated arm having a hand grip portion 33 at its outer end. Inwardly of the hand grip portion 33, the arm of the lever C is of channel-shaped cross section, comprising a lengthwise extending, vertically disposed web 34 and top and bottom, horizontally disposed flanges 35—35 projecting laterally from said web. At the inner end, the arm of the lever C is recessed, as indicated at 36, to fit the circular contour of the tubular operating bar A, said recess being defined by an arc-shaped web 37, which forms a continuation of the web 34. At the point where the handle lever C is attached to the tubular bar A, the outer wall of the bar is slit to provide a pair of wings 38 and 39 which are bent outwardly, as shown in Figures 8 and 9, to provide abutments which shoulder, respectively, against a flat face 40 on the inner side of the handle lever C at the inner end portion thereof, and the flat end face 41 of the arc-shaped web 37. The lever C is welded to the tubular bar A at said abutment wing portions 38 and 39 of the latter, as indicated at 42 and 43. As will be evident, the shouldered engagement of the lever C with the wings of the bar A serves to relieve the welded joint from torsional strains when the bar is rotated by the lever to force the door 12 open or closed.

In applying the door fastener shown in Figures 1 to 9 inclusive to the door 12, the end members B—B are first welded to the ends of the tubular bar A and the assembled unit, comprising the bar A and the end members B—B, is then placed within the door by passing the same endwise from above the door in downward direction through the opening 30 in the horizontal web of the top Z-bar 17. In this connection it is pointed out that the horizontal webs of the top and bottom Z-bars and the top and bottom walls of the pocket 20 are provided with suitable slots 44—44 and 44—44 which communicate with the openings 30—30 and 22 and 23 to provide enlargements of these openings through which the fingers 26 of the end members B of the operating bar may freely pass in applying the unit comprising the bar A and the end members B—B to the door.

Before the lower end of the bar A and its lower end member B is dropped through the opening 23

of the bottom wall 25 of the pocket 20, the collar 31 is placed in position on the wall 25 with the opening thereof aligned with the opening 23 and the collar turned to a position to register the slot 131 thereof with the slot of said wall 25 to thereby allow the keeper engaging finger 26 of the end member to be passed therethrough in applying the same to the door. The assembled unit, comprising the bar A and the end members B—B, is then dropped to its operative position, as shown in Figure 4, and the collar 31, after being turned to bring the opening 131 thereof to the rear side of the bar A, as shown in Figure 4, is welded to the bar. After the parts have been thus assembled, the operating handle lever C is placed in position and welded to the wings 38 and 39 of the bar. As will be evident, in forcing the door 12 closed, the lever C is swung into the pocket 20. To lock the same in position to maintain the door closed, the usual latch means, indicated by 140, is employed.

Referring next to the modified structure shown in Figure 10, the same comprises a rotary operating bar E, which is similar to the tubular operating bar A hereinbefore described in that it is also of tubular form, and an operating lever F, which is secured to the bar. The operating lever F is similar to the lever C hereinbefore described in that it is of channel-shaped cross section, having a vertically disposed web 134 and top and bottom flanges 135. The inner end of the lever F is provided with a recess 136 in which the bar E is seated, the recess 136 being defined by an arc-shaped web 137 which forms a continuation of the web 134 and embraces slightly more than half of the circumference of the bar. The lever F is fixed to the bar by welding the same thereto at the rear side of the lever and at the extremity of the web 137, as indicated by 138 and 139.

40 I claim:

1. In a device of the character described, the combination with a cylindrical operating bar; of a handle lever fixed to said bar, said lever having an arcuate portion partly embracing said bar, 45 said bar having circumferentially spaced, peripheral stop shoulders with which the opposite ends of said arcuate portion of the lever have shouldered engagement, said lever being welded to said bar at the zones of shouldered engagement there-

50 of.
2. In a device of the character described, the combination with a tubular operating bar of cylindrical, transverse cross section; of an operating lever fixed to said bar, said lever having a recessed inner end portion in which said bar is engaged, said lever having abutment shoulders at opposite ends of the recess thereof; and oppositely facing stop wings on said bar having shouldered engagement with said abutment shoulders, 55 said recessed portion of the lever being welded to said bar.

3. In a device of the character described, the combination with a tubular operating bar of cylindrical, transverse cross section; of an operating lever fixed to said bar, said lever having a recessed inner end portion in which said bar is engaged, said lever having abutment shoulders at opposite ends of the recess thereof; and oppositely facing stop wings on said bar having shouldered engagement with said abutment shoulders, 60 said recessed portion of the lever being welded to said bar at the points of shouldered engagement of said wings with said lever.

4. In a device of the character described, the combination with a tubular operating bar, said

bar having circumferentially spaced, oppositely facing abutment wings, said wings being formed by outwardly bent portions of the wall of said tubular bar; of an operating lever having a seat at its inner end embracing the outer side of said bar between the ends of said wings, said inner end of the lever having flat faces at opposite ends of said seat abutting the ends of said wings, said wings being welded to said lever at said points of abutment.
